UNITED STATES PATENT OFFICE

ANDREW ZAPART, OF BROOKLYN, NEW YORK

MAIL BOX

Application filed May 27, 1929. Serial No. 366,203.

The present invention relates to mail boxes and has for its main object the general improvement of the mail boxes.

A further object of the present invention is the provision of a mail box which may be durable in construction and efficient in its operation.

A further object of the present invention is the provision of a mail box with various attachments which would afford reception of bulky mail packages.

A still further object of the present invention is the provision of a mail box which could be permanently mounted upon a wall.

A still further object of the present invention is the provision of a mail box consisting of an outer and an inner receptacle wherein the inner receptacle may shift vertically within the outer receptacle for removing the mail deposited in the box.

With the above general objects in view and others that will appear as the nature of the invention is better understood, the same consists in the novel construction, combination and arrangement of parts hereinafter more fully described, illustrated in the accompanying drawings and pointed out in the appended claims.

In the drawings forming a part of this application, and in which like designating characters refer to corresponding parts throughout the several views,

Fig. 1 is a perspective view of the mail box;

Fig. 2 is a vertical cross-sectional view of the mail box, the view having been taken on line 2—2 of Fig. 3;

Fig. 3 is the rear view of the box with the rear wall thereof removed;

Fig. 4 is a rear elevational view of the mail box; and

Fig. 5 is a transverse cross-sectional view of the mail box, the view having been taken on line 5—5 of Fig. 2.

Referring in detail to the present drawings there is shown therein the outer receptacle generally indicated by numeral 10 and consisting of the front wall 11, rear wall 12, side walls 13 and an inclined top wall 14, the latter being provided with a longitudinal slot 15

through which mail matter, such as letters, is deposited within the mail box.

Said side walls 13 at their upper ends and adjacent their rear edges are provided with projections 16 provided with openings for receiving therewith lugs 17 made in top cover 18 which normally rests upon said top wall 14 and covers slot 15. Thus it will be seen that said projections 16 and lugs 17 provide a hinge for said cover 18.

The side walls 13 on their inner faces are lined with wooden walls 19.

The device further includes a pair of spring members 20 having their upper ends coiled and contacting with front wall 11. The upper terminations of said springs 20 carry rod 21 which holds said springs in relative position. Newspapers or other like mail may be placed behind said springs and frictionally held against the front wall 11 preventing displacement. The lower ends of said spring members 20 include horizontal portions 22 and upright portions 23. Said upright portions 23 of springs 20 are receivable within cut-away portions made in the rear lower edges of side walls 13 and wooden walls 19, so that in assembled position the rear faces of said upright portions 23 remain flush with the rear edges of side walls 13 and wooden walls 19, as seen on Figs. 1 and 3. By means of screws 24 at the upright portions 23 said springs 20 are rigidly mounted upon and in said wooden walls 19.

The horizontal portions 22 of springs 20 are relatively long extending forwardly of said front wall 11 and are adapted to receive upon the free portions thereof shelf 25 which has an upwardly bent strip 26 which contacts with the lower edge of said front wall 11 and is affixed thereto and to the wooden walls 19 by means of screws 27. Centrally of said upright strip 26 as well as in said front wall 11 there is an opening 28 for the purpose which will be hereinafter described. Said shelf 25 is adapted to receive other bulky mail incapable of being positioned within the mail box through slot 15.

The rear or back wall 12 of the present invention is affixed to the wooden walls 19 by means of a plurality of screws 29 and over-

laps the rear upright portions 23 of the spring members 20. The upper edge of said rear wall 12 is adapted to receive a narrow plate 30 which is secured to the wooden walls 19 by means of screws 31 which pass through said rear wall 12. An opening 32 is made in the central portion of said narrow plate 30 which registers with a similar opening made in the rear wall 12 for the purpose of hanging the outer receptacle of the mail box upon a nail on the wall.

At the lower edge of said rear wall 12 there is plate 33 attached to the receptacle by means of a plurality of screws 34 driven into the wooden side walls 19, which latter screws pass through said rear wall 12. Integrally formed with said plate 33 and downwardly projecting therefrom is a narrow member 35 terminating in a hook 36 which is forwardly bent. One object of said hook 36 is to receive thereupon bulky packages which may be suspended upon said hook by string or cord which ordinarily encompasses the package.

The front wall 11, substantially at the central portion and transversely thereof, has a series of rather narrow openings 37, and adjacent its lower end said wall 11 is further provided with round openings 38. Card 39 bearing the name of the owner of the mail receptacle is positioned rearwardly of said front wall 11 in such a way as to permit registering of the name with slots 37 so that the same may be visible therethrough. Below said card 39 transparent sheet 40 made of celluloid or any other suitable material, is positioned for the purpose of covering opening 39, which prevents moisture or dust from entering within the receptacle, but at the same time permits visibility within the receptacle so that the owner of the box may look thereinto through said openings 38 to see if there is any mail deposited in the receptacle. Said sheet 40 has upwardly projecting ears 41 made at the upper edge of said sheet 40 which support the lower edge of card 39 and prevent bending or deflection of said card 39 within the outer receptacle of the mail box.

Metallic resilient frame 42 is provided at the rear face of the front plate 11 wherein said card 39 and sheet 40 may be inserted and held in position upon said front plate 11.

Plate 33 and rear wall 12 are provided with registering apertures 43, which are in alignment with openings 29 in the front wall 11 and strip 26 for the purpose which will be hereinafter stated.

It is understood that the outer receptacle hereinabove described is devoid of any lower wall, at the bottom it being open for the purpose of receiving therethrough inner receptacle which includes lower or bottom wall 44, side walls 45 and comparatively short rear wall 46, it being devoid of any front or top walls. This inner receptacle is positioned

within the outer receptacle and is adapted for upright sliding movement therewithin. The bottom wall 44 of said inner receptacle constitutes a closure for the outer receptacle when the inner receptacle is in closed position within the outer receptacle as seen on Fig. 2.

The side walls 45, which contact with the inner faces of wooden walls 19 of the outer receptacle are each provided with longitudinal slots 47 made centrally of said side walls 45 wherein screws 48, mounted upon side walls 19, are positioned.

Said screws 48 hold the inner receptacle in position within the outer receptacle, but by virtue of said slots 47 the inner receptacle is permitted to make upright shifting movement, as shown by dotted lines on Fig. 2.

One of said side walls 45 is downwardly and rearwardly tapered as at 49, its one sharp end reaches the top wall 14 of the outer receptacle when the inner receptacle is in closed position within said outer receptacle.

At the tapered edge 49 said one side wall 45 of the inner receptacle is provided with tooth 50 which is adapted to engage hook 51 of latching lever 52 which is pivoted upon one of the wooden walls 19 on pin 53.

The other upper end of said latching lever 52 has an inwardly turned end 54 by means of which said latching lever 52 may be manually shifted upon pivot pin 53 for the purpose of disengaging hook 51 from tooth 50.

This may be done by inserting finger within the outer receptacle through slot 15 of the upper wall 14. When this is done the inner receptacle by virtue of its gravity will fall toward and upon hook 36 which constitutes an additional support for said inner receptacle when the same is in an open position illustrated by dotted lines on Figs. 1 and 2.

One of the longer side walls 45 of the inner receptacle may be provided with an opening 55 for receiving bolt 56 of lock 57 set within one adjacent wooden wall 19 and the corresponding side wall 13 of the outer receptacle.

It is observed that the latching lever 52 is at all times longitudinally disposed relative to the wooden wall 19, its hook 51 being downwardly disposed. When the inner receptacle is shifted upwardly to the closed position said hook will automatically engage tooth 50 due to the fact that one edge of said hook 51 is tapered and corresponds to the tapered upper edge of side wall 45 of said inner receptacle.

Therefore, when the inner receptacle is raised to its closed position within the outer receptacle hook 51 will ride upon the tapered edge 49 of side wall 45 of the inner receptacle until its engagement with tooth 50 is attained.

The rear wall 46 of the inner receptacle at its central portion is provided with opening 58 which is adapted to register with apertures 43 made in plate 33 and the rear wall 12 of the outer receptacle when said inner receptacle is in an open position shown on

130

dotted lines on Figs. 1 and 2. Consequently said opening 58 will be in alinement with openings 28 made in the front wall 11 and strip 26 when said inner receptacle is in an open position. When all of said openings 5 register, screw 59 is passed through apertures 43 and is thereupon driven to the wall, the registering openings 28 and 58 permitting insertion of a screw driver or other implement for driving said screw 59 into the wall. Thus, when said screw is completely driven into the wall its head will be countersunk in the rear wall 12 of the outer receptacle permitting free and unobstructed 10 upright shifting movement of said rear wall 46 of the inner receptacle.

One of said side walls 45 of the inner receptacle has at its free edge a cut-away portion 60 permitting insertion of finger for the 20 purpose of removing the mail deposited in the mail box, it being understood that any mail deposited therein will rest upon the bottom wall 44 of said inner receptacle and when said receptacle is open or shifted downwardly to the position shown by dotted lines 25 on Figs. 1 and 2, the mail therewithin will shift downwardly with said inner receptacle.

While there is described herein a preferred embodiment of the present invention, it is 30 nevertheless to be understood that minor changes may be made therein without departing from the spirit and scope of the invention as claimed.

What I claim as new is:

35 1. A mail box comprising an outer receptacle, an inner receptacle, said inner receptacle being adapted for upright shifting movement within said outer receptacle, and locking means between said two receptacles 40 automatically operable on upward shifting of said inner receptacle within said outer receptacle for interlocking the two receptacles.

45 2. A mail box comprising an outer receptacle, an inner receptacle, said inner receptacle being adapted for upright shifting movement within said outer receptacle, a latching lever suspended within the upper end of said outer receptacle, and means upon 50 said inner receptacle for automatically engaging said latching lever when said inner receptacle is in a closed position within said outer receptacle.

55 3. A mail box comprising an outer receptacle, said outer receptacle including side walls, wooden walls inwardly of said outer receptacle and abutting said side walls, spring members, said spring members having rear upright portions, the rear lower edges of said side walls and said wooden walls having cut away portions for receiving said rear upright portion of said spring members, and a rear wall mounted upon said side walls and said wooden walls and attached to said wooden walls, said rear walls

overlapping said rear upright portions of said spring members, said spring members having resilient front ends disposed forwardly of said receptacle for exerting tension upon the mail matter placed between 70 said resilient ends of said receptacle.

4. In a mail box including inner and outer receptacles and wherein said inner receptacle is adapted to make upright shifting movement within said outer receptacle, a latching means between said two receptacles comprising a lever suspended within said outer receptacle, and a hook integrally formed at the lower end of said lever, said hook being adapted to engage said inner receptacle when 80 the same is fully shifted within said outer receptacle.

5. In a mail box including inner and outer receptacles and wherein said inner receptacle is adapted to make upright shifting 85 movement within said outer receptacle, a latching means between said two receptacles comprising a lever suspended within said outer receptacle, a hook integrally formed at the lower end of said lever, one of the walls 90 of said inner receptacle being tapered at its upper end for permitting the riding of said hook thereupon when said inner receptacle is shifted within said outer receptacle, and a tooth upon said tapered end for engaging 95 said hook when said inner receptacle is fully shifted within said outer receptacle.

In testimony whereof I affix my signature.

ANDREW ZAPART.
